UNITED STATES PATENT OFFICE.

FLOYD D. STOWE, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

SLIDE-FORMER MACHINE.

1,271,797.

Specification of Letters Patent.

Patented July 9, 1918.

Application filed April 24, 1914. Serial No. 834,082.

To all whom it may concern:

Be it known that I, FLOYD D. STOWE, of Wilmington, in the county of Newcastle and in the State of Delaware, have invented 5 a certain new and useful Improvement in Slide-Former Machines, and do hereby declare that the following is a full, clear, and exact description thereof.

My invention relates particularly to a 10 machine for forming slides used for closing the bung-holes of kegs, such for example, as powder kegs.

The object of my invention is to provide 15 a machine in which blanks of the proper shape are formed into slides which have side flanges adapted to coöperate with sides of the ears attached to bung-holes upon kegs of the above character, and which will provide the slides with suitable lettering and 20 stamped figures which are used for identifying the particular keg and the character of the contents. Further objects of my invention will appear from a consideration of the particular apparatus which is described in 25 detail hereinafter.

While my invention is capable of being carried out in many different ways, for the purpose of illustration I have shown only one form of my invention in the accompanying drawings, in which,

Figure 1 is a front elevation of a slide former made in accordance with my invention;

Fig. 2 is a plan view of the lower or stationary portion of the same;

Fig. 3 is a vertical section through a portion of the apparatus taken in the position of line *a—a* in Fig. 2;

Fig. 4 is a front elevation of the portion of 40 the machine shown in Fig. 2;

Fig. 5 is a vertical section enlarged of certain parts shown in Fig. 3;

Fig. 6 is a vertical elevation partly in section of the upper reciprocating portion of 45 the machine;

Fig. 7 is a side elevation of the same;

Fig. 8 is a bottom view of the parts shown in Fig. 6 and,

Fig. 9 is a side elevation of one of the 50 kicker arms.

Fig. 10 is a plan view of the unformed blank;

Fig. 11 is a similar view of the formed blank, and

Fig. 12 is an elevation of the article shown 55 in Fig. 11.

In the drawings I have shown a main frame 1 having a reciprocating plunger 2, which receives a stem 3 of a male die, which comprises a four-sided sleeve 4 fitting over 60 a reduced end 5 on the stem 2 and yieldingly moved downward a slight distance from the stem by means of springs 6. Screws 7, of which there are three, hold the four-sided sleeve 4 upon the reduced extension 5. At 65 the bottom of the sleeve 4 on the two sides thereof there are inwardly curved recesses 8 for a purpose to be hereinafter described, and upon the bottom of the sleeve 4 there is a plate 9 which extends out beyond the lower 70 edges of the curved recesses 8 for a purpose also to be hereinafter described. The plate 9 is held in place by four screws 10 which connect the same to the sleeve 4. The center of the stem 3 at the lower portion is extended to a position somewhat above the lowest portion of the plate 9 so as to receive a male lettering die 11 which is secured in place by a bolt 12 extending downwardly 75 through the center of the stem 3 and screw-threaded into the top of said male die 11. At its two sides the stem 3 has a pair of lateral extensions 13 to receive vertical guides 14, which are screw-threaded thereto and which have cylindrical guiding surfaces 15 80 at their lower ends. The guides 14 are held in their adjusted positions by screws 16, which extend into the lateral extensions 13. In the reciprocation of the plunger 2, the guides 14 reciprocate in holes 17 which pass 85 through a pair of lateral guide plates 18 attached to the top of folder plates 19 supported on a bed plate 20 secured to the main frame. These folder plates 19 are secured to the bed plate 20 by screws 21. Beneath 90 the folder plates 19 the bed plate 20 has recesses 22 at the two sides of the same into which are secured by means of screws 23, holders 24 for a pair of rocker arms 25. Each of these rocker arms has a pivot 26 95 which rotates in a socket in one of the holders 24, while at its free or movable end the rocker arm 25 has a folding arm or projection 27 and a guiding arm or projection 28.

80

85

90

95

100

The folding arm 27 is designed to force the edge of the blank into one of the recesses 8 while the guiding arm 28 is designed to move the rocker arm 25, so as to force the 5 arm 27 into said recess 8. The arms 28 are moved by curved surfaces 29, located in the underside of a stripper plate 30. This stripper plate 30 in the forming of the blank occupies a position immediately below the 10 blank. The function of the guides 14 is not only to assist in guiding the relatively movable parts with regard to each other, but is also to act as an adjustable auxiliary actuating means for the rocker arms 25. This 15 additional actuating means is particularly advantageous where the curved surfaces 29 have become worn to some degree through continued operation of the rocker arms by contact with the arms 28. In the center of 20 the stripper plate 30 and supported upon the bed plate 20, there is a female lettering die 31, which is held upon the same by a bolt 32 which passes upwardly into the bed 20 through the center of a pipe 33 which is 25 screw-threaded at its upper end in the bottom of the bed 20. A washer or spacing block 34 fits over the bolt 32 between the head thereof and the lower end of the pipe 33. The lower end of the pipe 33 is also screw- 30 threaded to receive a spring collar 35, the purpose of which is to support an inner spring 36 and an outer spring 37. Upon the top of the outer spring 37 there is a collar 38 to which there are connected three pins 39 35 which extend upwardly to and contact with the under surface of the stripper plate 30. The force of the spring 37 therefore maintains the stripper plate 30 at all times pressed against the under surface of the 40 blank which is carried over the edge of the plate 9 during the forming of the blank into its proper shape and before it is discharged from the machine. Supported upon the top of the inner spring 36 there is a collar 40 45 which is integral with a plate 41 having attached thereto four pins 42, the upper ends of which extend to and contact with the under surface of the rocker arms 25. The inner spring 36 therefore exercises its force 50 upward to move the rocker arms 25 upwardly whenever an upward movement is permitted by the position of the reciprocating male die. The blank when formed is automatically released from the machine by 55 the following mechanism: Upon the top of the bed 20 there is riveted a pair of posts 43 the upper ends of which provide bearings for a shaft 44 extending out through the sides of the posts 43 and receiving on its 60 ends collars 45 and 46. The collar 46 has a recess in its inner face to receive a coil spring 47, which normally tends to move the shaft 44 in such a direction as to cause a pair of kicker arms 48 attached to the shaft 65 44 to move toward their vertical position.

The other collar 45 has a recess in its under face to coöperate with a pin 49 so as to limit the degree of movement of the kicker arms 48. Each of the kicker arms 48 has at its lower end a projection 50 to throw the 70 formed blank out of the machine at the end of the forming operation, and each of said kicker arms 48 also has at its upper end an actuating arm 51 which coöperates with a plate 52 held in position by screws 53 passing through the same and into the stems 3. In the upper face of the stripper plate 30 there are also supported three dating or lettering dies 54 which operate against three 75 aluminum plugs 55 (Fig. 8) which are supported in the under face of the sleeve 4.

Preferably the machine as shown is so located as to support the various parts at an angle to the horizontal, so that the narrow end of the formed blank will be directed 80 toward the lower side of the machine.

In the operation of the machine a flat blank 56, having the shape shown in Fig. 10 will be inserted in the machine when its sides will contact with the lateral guides 18 90 in such a way that the edges of the blank are supported upon the top of the folder plates 19. When next the plunger 2 is moved downwardly with its attached male die the plate 9 will move downwardly until 95 it contacts with the upper surface of the blank 56. Thereafter the plate 9 will continue its movement downwardly thus pressing the blank 56 down below the level of the folder plates 19, the free edges of which 100 will cause the edges of the blank 56 to be folded upwardly in a vertical direction. The continued downward movement of the plunger 2 will bring the blank 56 with its folded edges to a level below the edges of 105 the folder plates 19 where the rocker arms 25 will bring the folder arms 27 against the folded edges of the blank 56 so as to operate the same upwardly into recesses 8 over the top surfaces of the plate 9. The rocker arms 25 are moved in this manner not only by the curved surfaces 29, but also by the guides 110 14. Finally in the downward movement of the plunger 2 the male lettering die 11 co-operates with the female lettering die 31 to give the impression of a letter in the body of the blank 56, and at the same time the three dating or lettering dies 54 impress their numbers or letters into the blank in 115 coöperation with the aluminum plugs 55. When the upward movement of the plunger 2 now begins the stripper plate 30 follows the formed blank upwardly with the male die attached to the stem 12, said stripper plate 30 being moved upwardly under the influence of the spring 37. At the same time the rocker arms 25 are also moved upwardly 120 under the influence of the spring 36. When the stripper plate 30 and the rocker arms 25 have moved to their upper limits the posi- 125 130

tion of the rocker arms is such as to permit the continued upward movement of the male die and the plate 9 attached thereto with the blank 56 folded over the same without any interference from the rocker arms 25. As soon as the plate 9 has passed above and beyond the stripper plate 30, the springs 6 between the sleeve 4 and the stem 3 will cause the sleeve 4 and its attached blank to move downwardly a short distance so as to move the formed blank beyond the level of the male die and thus release the formed blank 56 from any engagement with the raised surface of the male die. At this point the plate 52 comes into contact with the upper ends of the kicker arms 48 thus violently forcing the lower ends 50 thereof against the edge of the formed blank 56, so as to kick the same off of the male die and the plate 9, after which owing to the incline of the parts the formed blank falls downward by gravity to a receptacle or any other apparatus designed to assist in the removal of the formed blanks.

25 While I have described my invention above in detail, I wish it to be understood that many changes may be made therein without departing from the spirit of my invention.

30 I claim:

1. In a metal forming machine, devices for turning over the edge of a blank comprising a reciprocating grooved member, a rocker arm adapted to force the edge of the blank into the groove, the rocker arm having a projection guiding the rocker arm into the groove, and a plate following the blank on the opposite side thereof to the grooved member.

40 2. In a metal forming machine, devices for turning over the edge of a blank comprising a reciprocating grooved member, a rocker arm adapted to force the edge of the blank into the groove, the rocker arm having a projection guiding the rocker arm into the groove, and a plate following the blank on the opposite side thereof to the grooved member, said plate having a curved surface coöperating with the projection.

45 3. In a metal forming machine, devices for turning over the edge of a blank comprising a reciprocating grooved member, a rocker arm adapted to force the edge of the blank into the groove, and an adjustable actuating device for the rocker arm secured to the grooved member.

4. In a metal forming machine, devices for turning over the edge of a blank comprising a reciprocating grooved spring-supported sleeve, a rocker arm adapted to force the edge of the blank into the groove, and an impression die located in the sleeve.

5. In a metal forming machine, devices for turning over the edge of a blank comprising a reciprocating grooved spring-sup-

ported sleeve, a rocker arm adapted to force the edge of the blank into the groove, the rocker arm having a projection guiding the rocker arm into the groove, and an impression die located in the sleeve. 70

6. In a metal forming machine, devices for turning over the edge of a blank comprising a reciprocating grooved spring-supported sleeve, a rocker arm adapted to force the edge of the blank into the groove, the rocker arm having a projection guiding the rocker arm into the groove, a plate following the blank on the opposite side thereof to the grooved member, and an impression die located in the sleeve. 75 80

7. In a metal forming machine, devices for turning over the edges of a blank comprising a reciprocating grooved spring-supported sleeve, a rocker arm adapted to force the edge of the blank into the groove, the rocker arm having a projection guiding the rocker arm into the groove, and a plate following the blank on the opposite side thereof to the grooved member, said plate having a curved surface coöperating with the projection, and an impression die located in the sleeve. 85 90

8. In a metal forming machine, devices for turning over the edge of a blank comprising a reciprocating grooved member, a rocker arm adapted to force the edge of the blank into the groove, the rocker arm having a projection guiding the rocker arm into the groove, a plate following the blank on the opposite side thereof to the grooved member, and yielding means to force the rocker arm and plate in the direction of the grooved device. 95 100

9. In a metal forming machine, devices for turning over the edge of a blank comprising a reciprocating grooved member, a rocker arm adapted to force the edge of the blank into the groove, the rocker arm having a projection guiding the rocker arm into the groove, a plate following the blank on the opposite side thereof to the grooved member, said plate having a curved surface coöperating with the projection, and yielding means to force the rocker arm and plate in the direction of the grooved device. 105 110 115

10. In a metal forming machine, devices for turning over the edge of a blank comprising a reciprocating grooved spring-supported sleeve, a rocker arm adapted to force the edge of the blank into the groove, the rocker arm having a projection guiding the rocker arm into the groove, a plate following the blank on the opposite side thereof to the grooved member, an impression die located in the sleeve, and yielding means to force the rocker arm and plate in the direction of the grooved device. 120 125

11. In a metal forming machine, devices for turning over the edges of a blank comprising a reciprocating grooved spring-sup-

ported sleeve, a rocker arm adapted to force the edge of the blank into the groove, the rocker arm having a projection guiding the rocker arm into the groove, a plate following the blank on the opposite side thereof to the grooved member, said plate having a curved surface coöperating with the projection, and an impression die located in the sleeve, and yielding means to force the rocker arm and plate in the direction of the grooved device.

12. In a metal forming machine, devices for turning over the edge of a blank comprising a reciprocating grooved member, a rocker arm adapted to force the edge of the blank into the groove, the rocker arm having a projection guiding the rocker arm into the groove, a plate following the blank on the opposite side thereof to the grooved member, and spring-supported pins to force the rocker arm and plate in the direction of the grooved device.

13. In a metal forming machine, devices for turning over the edge of a blank comprising a reciprocating grooved member, a rocker arm adapted to force the edge of the blank into the groove, the rocker arm having a projection guiding the rocker arm into the groove, a plate following the blank on the opposite side thereof to the grooved member, said plate having a curved surface coöperating with the projection, and spring-supported pins to force the rocker arm and plate in the direction of the grooved device.

14. In a metal forming machine, devices for turning over the edge of a blank comprising a reciprocating grooved spring-supported sleeve, a rocker arm adapted to force the edge of the blank into the groove, the rocker arm having a projection guiding the rocker arm into the groove, a plate following the blank on the opposite side thereof to the grooved member, an impression die located in the sleeve, and spring-supported pins to force the rocker arm and plate in the direction of the grooved device.

15. In a metal forming machine, devices for turning over the edges of a blank comprising a reciprocating grooved spring-supported sleeve, a rocker arm adapted to force the edge of the blank into the groove, the rocker arm having a projection guiding the rocker arm into the groove, a plate following the blank on the opposite side thereof to the grooved member, said plate having a curved surface coöperating with the projection, and an impression die located in the sleeve, and spring-supported pins to force the rocker arm and plate in the direction of the grooved device.

16. In a metal forming machine, devices for turning over the edge of a blank comprising a reciprocating grooved spring-supported

sleeve, a rocker arm adapted to force the edge of the blank into the groove, an impression die located in the sleeve, and another impression die coöperating with the first-mentioned impression die.

17. In a metal forming machine, devices for turning over the edge of a blank comprising a reciprocating grooved spring-supported sleeve, a rocker arm adapted to force the edge of the blank into the groove, the rocker arm having a projection guiding the rocker arm into the groove, an impression die located in the sleeve, and another impression die coöperating with the first-mentioned impression die.

18. In a metal forming machine, devices for turning over the edge of a blank comprising a reciprocating grooved spring-supported sleeve, a rocker arm adapted to force the edge of the blank into the groove, the rocker arm having a projection guiding the rocker arm into the groove, a plate following the blank on the opposite side thereof to the grooved member, an impression die located in the sleeve, and another impression die coöperating with the first-mentioned impression die.

19. In a metal forming machine, devices for turning over the edges of a blank comprising a reciprocating grooved spring-supported sleeve, a rocker arm adapted to force the edge of the blank into the groove, the rocker arm having a projection guiding the rocker arm into the groove, a plate following the blank on the opposite side thereof to the grooved member, said plate having a curved surface coöperating with the projection, an impression die located in the sleeve, and another impression die coöperating with the first-mentioned impression die.

20. In a metal forming machine, devices for turning over the edge of a blank beyond a position perpendicular to the blank, and a kicker for removing the formed blank therefrom, comprising a pivoted arm.

21. In a metal forming machine, devices for turning over the edge of a blank beyond a position perpendicular to the blank, and a kicker for removing the formed blank therefrom, comprising a pivoted arm having an extension contacting with the blank.

22. In a metal forming machine, devices for turning over the edge of a blank beyond a position perpendicular to the blank, comprising a reciprocating member, and a kicker for removing the formed blank therefrom, said kicker being adapted to be moved by the reciprocating member.

23. In a metal forming machine, devices for turning over the edge of a blank beyond a position perpendicular to the blank, comprising a reciprocating member, and a kicker for removing the formed blank therefrom, comprising a pivoted arm, said kicker being

adapted to be moved by the reciprocating member.

kicker being adapted to be moved by the 10 reciprocating member.

In testimony that I claim the foregoing I have hereunto set my hand.

FLOYD D. STOWE.
